US0D1089292S

(12) **United States Design Patent** (10) Patent No.: **US D1,089,292 S**
 Huntley et al. (45) Date of Patent: ** Aug. 19, 2025

(54) **DISPLAY SCREEN WITH A GRAPHICAL USER INTERFACE**

(71) Applicant: **Meta Platforms, Inc.**, Menlo Park, CA (US)

(72) Inventors: **Brian Huntley**, San Jose, CA (US); **Seth Lee Weisfeld**, Brooklyn, NY (US)

(73) Assignee: **Meta Platforms, Inc.**, Menlo Park, CA (US)

(**) Term: **15 Years**

(21) Appl. No.: **29/816,405**

(22) Filed: **Nov. 22, 2021**

(51) LOC (15) Cl. **14-04**

(52) U.S. Cl.

USPC **D14/488**

(58) **Field of Classification Search**

USPC **D14/485-495**

CPC G06F 3/048; G06F 3/0481; G06F 3/04817; G06F 3/0482; G06F 3/0483; G06F 3/04842; G06F 3/0485; G06F 3/04855; G06F 3/0486; G06F 3/0488; G06F 3/04886; G06F 9/451; G06Q 10/10; G06Q 50/01; H04N 21/4312; H04N 21/4438; H04N 21/47; H04N 21/4788; H04N 21/482; H04L 51/52; H04L 41/22

(57) **CLAIM**

The ornamental design for a display screen with a graphical user interface, as shown and described.

DESCRIPTION

The sole FIGURE is a front view of a display screen with a graphical user interface showing the claimed design.

The broken line showing of the display screen with a graphical user interface is included for the purpose of illustrating portions of the article and forms no part of the claimed design.

1 Claim, 1 Drawing Sheet
